UNITED STATES PATENT OFFICE.

EVA JOSEPHINE LAKE, OF GREENSBURG, PENNSYLVANIA.

ATTACHMENT FOR CANDLESTICKS AND CANDLEHOLDERS.

Application filed April 29, 1922. Serial No. 557,308.

To all whom it may concern:

Be it known that I, EVA JOSEPHINE LAKE, a citizen of the United States, residing at Greensburg, in the county of Westmoreland and State of Pennsylvania, have invented certain new and useful Improvements in Attachments for Candlesticks and Candleholders, of which the following is a specification.

10 The present invention relates to attachments for candle sticks and candle holders and has for its principal object to provide an attachment for catching the candle drippings.

15 A further object of the invention is to provide a cheaply manufactured device of this nature which will be simple and efficient in construction, reliable in operation, and well adapted to the purpose for which

20 it is designed.

With the above and numerous other objects in view as will appear as the description progresses, the invention resides in certain novel features of construction, and

25 the combination and arrangement of parts as will be hereinafter more fully described and claimed.

In the drawing:—

30 Figure 1 is an elevation of the attachment showing the same as used,

Figure 2 is a vertical section taken therethrough, and

35 Figure 3 is a transverse section taken substantially on the line 3—3 of Figure 2 looking in the direction of the arrow.

Referring to the drawing in detail it will be seen that 1 designates a candle holder supporting the candle 2. The candle 2 has its bottom end fitted in the socket 3 or pocket 3 of the candle holder 1 and as is quite common this socket is provided with an annular flange 4 on its sides.

40 My attachment consists of a cup-shaped stiffening element 5 including the body portion 6 having a central circular opening 7 therein adapted to register with the opening in the socket 3 and rest on the flange 4 and an upstanding flange on the edge of the body portion as indicated at 8. A skirt 9 is 45 mounted on the flange 8 of the stiffening element 5 and extends thereabove and therebelow for a desired distance. The lower

edge of this skirt is reinforced by a band or strip 10. It is to be noted that the flange 8 and the skirt 9 taper toward their lower ends and the skirt will be supported upon the stiffening element by glue or some such other material.

50 In actual practice I contemplate making the stiffening member 5 out of card board and the ornamental skirt out of tissue paper but of course any suitable material may be used. The skirt 9 in the present illustration, is shown as formed from crimped tissue paper but of course any other fanciful design may be used.

55 From the above description it will be readily ascertained that these attachments or devices may be manufactured at a very low cost and after having once been used 60 to catch the drippings can be economically replaced, when the cup-shaped member has become full. It will also be noted that numerous ornamental designs and effects may be secured by paper trimmings or 65 drapery such as the skirt 9 so as to make the device very attractive and ornamental.

70 Although I have described the invention with some degree of particularity, it is to be understood, that the present embodiment 75 has been disclosed only by way of example and that numerous changes in form, material, and in the combination and arrangement of parts may be resorted to without departing from the spirit of the invention as 80 hereinafter claimed.

85 Having thus described my invention what I claim as new is:—

An attachment of the class described including a stiffening element provided with 90 a body portion having a centrally located opening and a flange upstanding from its edge, a skirt supported on the upstanding flange of the stiffening element, and a bracing element encircling the lower edge 95 of the skirt in the manner and for the purpose specified.

In testimony whereof I affix my signature in presence of two witnesses.

EVA JOSEPHINE LAKE.
